UNITED STATES PATENT OFFICE.

FERDINAND SIEBER, OF CHARLOTTENBURG, GERMANY, ASSIGNOR TO GENERAL ELECTRIC COMPANY, A CORPORATION OF NEW YORK.

ELECTRICAL APPARATUS.

1,246,171.

Specification of Letters Patent. Patented Nov. 13, 1917.

Application filed April 24, 1915. Serial No. 23,651.

To all whom it may concern:

Be it known that I, FERDINAND SIEBER, a subject of the Emperor of Austria-Hungary, residing at Charlottenburg, Germany, have 5 invented certain new and useful Improvements in Electrical Apparatus, of which the following is a specification.

My invention relates to alternating current electrical apparatus wherein the leads 10 of the apparatus are necessarily or desirably passed through bodies or masses of magnetic material. Such cases arise frequently in practice, as for example with transformers and switches where the leads must pass 15 through the iron or steel containing tank or case, and with induction regulators where the leads from the rotary element pass through a bearing, or support or anchor for the leads. In each such case the magnetic 20 flux developed in the magnetic material results in losses which make themselves evident by voltage drop and local heating.

The object of my invention is to reduce 25 these losses in a simple and practicable way. I accomplish this object by placing near 30 each lead one or more short-circuited windings which surrounds such a section of the magnetic material as to interlink with the magnetic flux produced by the lead. Structures embodying my invention may assume various forms.

In the accompanying drawings and following description, I have illustrated and 35 described an embodiment of my invention in induction regulators. Figure 1 is an elevation, partly in section, of an induction regulator embodying my invention. Fig. 2 is a plan view, also partly in section, of a part 40 of the regulator of Fig. 1.

The rotor 10 of the regulator of Fig. 1 is carried on the shaft 11 within the stator 12, and is capable of being rotated more or less by means of the hand wheel 13 and the worm and sector 14 within this stator. The 45 winding 15 of the rotor has six leads 16, 17, 18, etc., which are carried through a support or anchor 19 carried on the shaft 11. This support or anchor comprises an annular iron or steel disk and relieves the connections between the leads and the rotor winding from the stresses due to the rotating of the rotor. The regulator so far described does not differ materially from a form of regulator now common.

In such a device, however, the leads 16, 17, 18, etc., produce magnetic flux in the support or anchor 19, and this in turn results in local heating and a drop in voltage. The path of the flux about lead 17 may be roughly represented by the dotted line 20. The flux about 55 each of the other leads follows similar paths. According to my invention the fall in voltage and local heating at each lead is reduced by means of one or more short-circuited turns or windings 21, 22, surrounding such 60 sections of the magnetic material as to interlink with more or less of the magnetic flux produced by the lead in question. Each short-circuited turn or winding comprises one or more turns of good electrical conducting material closed upon itself and each 65 surrounds a section more or less extensive; preferably each surrounds such a section as to embrace within itself substantially all the flux produced in the magnetic material 70 by the adjacent lead.

In the particular case illustrated, each of 75 two adjacent leads 16, 17, 18, etc., are reciprocally positive and negative (substantially). In such a case it is preferable that 80 each short-circuited turn or winding surround the section of magnetic material between the reciprocally positive and negative leads. Thus the winding 21 surrounds the 85 complete section between the leads 16 and 17 and the winding 22 surrounds the complete section between the leads 17 and 18. Substantially all the flux produced by the 90 lead 17 is by this arrangement interlinked with both of the short-circuited windings 95 21 and 22. Similar short-circuited windings surround the sections between the other pairs of leads.

While I have described the principle of 95 my invention and the best mode I have contemplated for applying this principle, other modifications will occur to those skilled in this art and I aim in the appended claims to cover all modifications which do not involve a departure from the spirit and scope of my 100 invention.

What I claim as new and desire to secure by Letters Patent of the United States, is,—

1. An alternating current electrical apparatus comprising the combination with 105 a winding, a mass of magnetic material and two reciprocally positive and negative leads therefrom passing through said magnetic

material of a short-circuited winding surrounding the section of magnetic material between said leads.

2. An alternating current electrical apparatus comprising the combination with a winding, a mass of magnetic material and a plurality of alternately positive and negative leads from said windings passing through and substantially surrounding a portion of 10 said magnetic material, of a plurality of short circuited windings about said portion

of said magnetic material, each surrounding a section of the magnetic material between two adjacent reciprocally positive and negative leads.

In witness whereof, I have hereunto set my hand this 10th day of March, 1915.

FERDINAND SIEBER.
